UNITED STATES PATENT OFFICE.

JOHANNES HÄRDÉN, OF SCHENECTADY, NEW YORK, ASSIGNOR TO GENERAL ELECTRIC COMPANY, A CORPORATION OF NEW YORK.

ARC-LAMP.

1,088,276.

Specification of Letters Patent.

Patented Feb. 24, 1914.

Application filed May 4, 1905. Serial No. 258,804.

To all whom it may concern:

Be it known that I, JOHANNES HÄRDÉN, a subject of the King of Norway and Sweden, residing at Schenectady, county of 5 Schenectady, State of New York, have invented certain new and useful Improvements in Arc-Lamps, of which the following is a specification.

My present invention comprises improvements in arc lamps and especially in the feeding mechanism and circuit arrangements of arc lamps.

The various features of novelty which characterize my invention are pointed out 15 with particularity in the claims annexed to and forming a part of this specification. For a better understanding of my invention, however, reference may be had to the accompanying drawings and descriptive matter 20 ter in which I have illustrated and described one of the forms in which my invention may be embodied.

Of the drawings, Figure 1 is an elevation with parts broken away and in section 25 of an arc lamp; Fig. 2 is an elevation with parts broken away and in section of the lamp shown in Fig. 1 taken from a different point of view; Fig. 3 is a sectional elevation illustrating a detail of construction; 30 Fig. 4 is a diagram illustrating the circuit arrangements and the operation of the lamp, and Figs. 5 and 6 are details of the lamp.

In the drawings, 1 represents the centrally located draft tube or chimney which forms 35 the back-bone of the arc lamp structure. In the particular construction shown in the drawings the chimney member comprises an upper section 2 and a lower section 3. The sections 2 and 3, which telescope together 40 and are connected by screws 4, may advantageously be made of non-magnetic material. To the upper end of the section 2 a top member 5 is secured by rivets 6. A hood 7 secured between a shoulder or collar 45 portion 8 formed on the top member 5 and the upper end of the section 2 serves to prevent the entrance of dust or moisture into the draft tube through the openings 9 formed in the upper end of the section 2. 50 A main lamp top hood 10, bell-shaped in form and provided with a centrally located aperture through which the section 2 passes, is secured to the latter by screws 11. The lower end of the section 3 is out-turned to 55 support a disk-shaped platform 12 which is

centrally apertured to receive the body of the section 3.

An arc-striking magnet coil 13 is secured between the hood 10 and the platform 12 by means of a collar 14 surrounding the section 3 which is provided with a projection 15 to the underside of which the upper end of the coil is secured. The coil, which is of the solenoid type, has its axis parallel to the axis of the chimney and is provided with 60 an armature 16. The armature 16 comprises a tubular core 17 formed of magnetic material which passes axially into the bore of the coil 13 and carries at its lower end a disk 17' of magnetic material. The disk 17' is 65 formed with a notch, the walls of which engage with a guide rib 18 formed on the chimney section 3 to prevent rotation of the disk 17'. When the lamp is to be used in an alternating current system, the armature 70 preferably has a slot 19 formed in it to reduce eddy currents, as shown, or it may be laminated.

A pair of similar links 20 are pivotally secured beneath the disk 17' to brackets 20' 75 carried by the disk. The lower ends of the arms 20 are pivotally secured to the outer ends of pawls 21. The inner ends of the pawls 21 are pivotally connected to a yoke member 22 which surrounds a rod or bar 23. 80 The yoke 22 and pawls 21 form the arc striking clutch of the lamp. The rod or bar 23 which passes through the platform 12 slides in a tubular guide 24 which passes through the platform 12 to which it is secured in any 85 suitable manner. When the coil 13 is de-energized and the armature 16 is in its lower position shown in Fig. 1, the gripping portions 25 of the pawls 21 are separated by reason of the member 22 coming to rest upon 90 the stop 22^a arranged upon the platform and the rod 23 is free to move through the yoke 22. When the coil 13 is energized, however, and the armature 16 is consequently raised, the bar 23 is clamped between the gripping portions 25 of the pawls 21 and after a slight initial upward movement of the armature 16 the bar 23 moves 95 upward with the armature.

To the lower end of the bar or rod 23 is 100 secured one end of a horizontal cross-head 26. The other end of the cross-head 26 is secured to the lower end of a bar or rod 27. The bar or rod 27 which passes upward through the platform 12 is guided by a 105

tubular member 28 similar to the member 24. The cross-head 26, which is insulated from the members 23 and 27, is provided with a socket 30 in which the lower electrode 29 of the lamp is secured in alinement with the axis of the draft tube or chimney 1.

The member 27 is loosely surrounded by a member 31 normally resting on the upper end of the guide member 28. A projection 10 from the member 31 is secured to the upper end of a rod 32 which extends downward through the platform 12 and slides in a guide member 33 secured to the platform. Above the member 31 the member 27 is surrounded by the yoke of the arc length limiting clutch 34. The pawl 35 of the clutch member has secured to its outer end the lower end of a helical tension spring 36. The upper end of the spring 36 is secured 20 to the chimney member 1 above the lower end of the hood 10 in a manner not shown in the drawings. The spring 36 normally holds the outer end of the pawl 35 elevated, in which position the member 27 is locked 25 between the yoke member of the clutch 34 and the pawl 35.

The downward movement of the pawl 35 and thereby the normal downward movement of the member 27 is limited by the engagement of the pawl 35 with a suitable stop which in the construction shown is in the form of a pin 37 passing through one of a number of holes 38 formed in a yoke or bracket 39 carried by the platform 12. 30 The upward movement of the pawl 35 is limited by its engagement with a pin 40 inserted in one of a number of holes 41 formed in the member 39. The limit of movement of the pawl 35 may be varied by inserting 40 the pins 37 and 40 in different ones of the sets of holes 38 and 41, respectively. A post or extension 42 carried by the chimney member 1 is apertured to receive the member 27 and forms a guide for its upper end. A 45 collar 43 secured to the upper end of the member 27 prevents the latter from moving downward through the extension 42.

A solenoid voltage coil 45 having its axis parallel to the axis of the chimney member 3 is secured to the latter by screws 46 which pass through extensions of the end pieces 47 of the coil. The armature co-operating with the voltage coil 45 comprises a tubular core member 50 which enters the lower end 55 of the coil 45 and a disk member 51 secured to its lower end. The core 50 and disk 51 may be slotted at 52 when the lamp is to be used in an alternating current circuit. One member of a dashpot 53 is secured to 60 the lower end of the armature 49. The other member of the dashpot is secured to the platform 12.

A tubular member 54 of magnetic material is rigidly secured in the upper end 65 of the coil 45. A plug of insulating ma-

terial 55 is secured in the upper end of the core 50. The lower end of a rod 56 is centrally secured in the block of insulating material 55. A block of insulating material 57 is secured in the upper end of the member 54. The insulating material 57 is formed with a centrally located aperture through which the rod 56 has a sliding movement. The upper end of the rod 56 has secured to it a contact member 58 which, in the form 70 shown, is bullet-shaped and may be made of any suitable material such as carbon. In the construction shown the member 58 is threaded upon the upper end of the rod 56, and may be adjusted along its length. A 75 pair of locking nuts 59, which may be adjusted along the length of the rod 56, form an abutment against which the upper end of the helical spring 59' surrounding the rod 56 engages. The lower end of the spring 80 rests against the block of insulating material 57. The spring 59' determines the voltage at which the coil 45 becomes operatively energized. By adjusting the nuts 59 along the rod 56 it is possible to cause the 85 energization of the coil to take place at any desired voltage.

A plate or contact support 60 is secured to an extension from the upper end piece 47 of the coil 45. Screws 61 secure a pair 90 of spring metallic contact members 62 to the support 60 in co-operative relation with the contact member 58. When the coil 45 is de-energized and armature 49 is in its lower position the contact 58 is out of engagement with the spring contacts 62 as shown. In this position of the parts the adjacent ends of the core 50 and member 54 are separated by some space. When the coil 45 is energized, however, and the movable core 50 100 is raised the contact 58 is forced firmly into engagement with the spring contacts 62. In order to prevent a too violent contact between the adjacent ends of the members 50 and 54 when the coil is energized a washer 105 63 of yielding material such as asbestos is placed about the rod 56. Thus the fixed tubular member 54 of magnetic material serves, in addition to its function of facilitating the magnetic flux through the axis 110 of the solenoid 45, also as a limiting stop for the movable core 50.

A bell-shaped member 64 with an aperture at its upper end, preferably formed of some good heat conducting and radiating 120 material such as sheet copper, is secured to the underside of the platform 12 by screws 65 passing through a radial flange portion 66 extending from the upper end of the member 64. As shown, the opening at the 125 upper end of the member 64 registers with the opening in the lower end of the chimney section member 3. The member 64 forms in effect a section of the chimney member 1.

An electrode receiving tube 67 axially located in the chimney member 1 and extending from a point near the upper end of the chimney to a point below the lower end of the section 3, is supported in a collar or socket member 68 provided with extensions 69, the ends of which are bent to lie against the inner surface of the member 64 to which they are secured by screws 70. Brackets extending from diametrically opposed points at the upper end of the collar 68 have pivotally secured in them links 71. To the lower ends of the links 71 are pivoted the outer ends of pawls 72. The lower ends of the pawls 72 are pivotally secured to a yoke or collar member 73, the upper end of which surrounds the lower end of the collar 68 on which it slides. The pawls 72 are provided with gripping portions 74 which are normally held in engagement with the upper electrode 75 of the lamp which is located in the tube 67 by the weight of the collar 73 and parts connected to it.

A tubular extension 76 of the collar member 73 is secured to the lower end of the latter. The extension 76 is formed of some material such as copper which is a good conductor of heat and which is neither readily oxidized by high temperatures nor readily affected by the arc vapors at such temperatures. A tubular guard or shield 77, formed of some refractory non-conducting material such as fire clay or the like, surrounds the extension 76. The extension 76 and the guard 77 are preferably arranged to be readily replaceable.

A lamp casing 78 of the usual form extends between platform 12 and the hood 10 to which it is secured by screws 79. Suitable means such as screws 80 are employed for securing to the lower end of the casing an arc inclosing globe 81. The globe 81, the upper end of which preferably fits snugly against the underside of the platform 12, has provided at its lower end an aperture 82 through which may enter the air necessary to obtain the proper draft through the lamp.

The circuit arrangements of the lamp are illustrated in the diagram shown in Fig. 4, where 90 and 91 represent the terminals of the lamp. A conductor 92 connects the terminal 90 to the cross-head 26 and the lower electrode 29. A conductor 93 leads from the terminal 91 to the upper electrode 75 of the lamp. It will of course be understood that in the actual lamp suitably insulated flexible conductors are ordinarily employed to make the proper connections to the electrodes. A conductor 94 leads from the terminal 90 to one of the contacts 62. A conductor 95 connects the other contact 62 to one terminal of the arc striking coil 13. The other terminal of the arc striking coil 13 is connected to the conductor 93 by a

conductor 96. One of the terminals of the voltage coil 45 is connected to the conductor 96 at the point 97. The other terminal of the voltage coil 45 is connected to the conductor 94 at the point 98.

The drawings represent the lamp in the out-of-service condition and also in the operative condition since the position of the parts are practically the same in both cases. In the out-of-service position the coils 45 and 13 are both deenergized and the circuit of the coil 13 is open between the contacts 62. The lower electrode is held in the position shown by the clutch 34 through the engagement of the pawl 35 with the pin 37. The upper electrode is locked in the tube 67 with its lower end adjacent the lower end of the extension 76.

As soon as the lamp is connected in an operative circuit the passage of current through the conductor 94, winding 45, conductor 97, and conductor 93, operatively energizes the coil 45, whereupon its armature is raised and the contact 58 is moved into engagement with the contacts 62 electrically connecting them together. Current will then flow through the circuit including conductors 94 and 95, coil 13, conductor 96 and conductor 93. This will operatively energize the coil 13 whereupon the armature 95 16 will be raised. The raising of the armature through the pawls 21, yoke 22, member 23, etc., will cause an upward movement of the electrode 29. The upper end of the electrode 29, which is considerably larger in 100 diameter than the electrode 75, will either engage the lower end of the electrode 75 or, in case the consumption of the latter is such that it no longer projects through the extension 76, will engage the lower end of the 105 extension 76.

As soon as the electrode 29 engages either the electrode 75 or the extension 76 current will begin to flow between the electrodes 29 and electrode 75 directly, or through the extension 76. The passage of current through the electrodes when they are brought into engagement reduces the voltage between the terminals 90 and 91 to such an extent that the coil 45 will no longer be operatively 115 energized, whereupon its armature will move downward toward its original position opening the circuit between the contacts 62, and thereby deenergizing the coil 13. The upward momentum of the electrode 29 is 120 however always sufficient to give a slight upward movement to the collar 73, whereupon the upper electrode is freed from its engagement with the pawls 72. The parts are so arranged that when thereafter the 125 electrode 29 moves downwardly, the electrode 75 moves through the extension 76 to the position shown in the drawings before it is again locked between the pawls 72.

When, as is usually the case, the consump- 130

tion of the upper electrode has been such that its lower end is some distance above the lower end of the extension 76 at the time at which the lamp feeds, the upper electrode 5 when released from its clutch in the manner hereinbefore described will drop with some force into engagement with the lower electrode. This improves the contact between the electrodes and facilitates the 10 starting of the current flow between the electrodes. Ordinarily I employ a follower block 75' of copper located in the tube 67 above the electrode 75. The weight of this follower block increases the force with which 15 the upper electrode impinges against the lower electrode in the manner just described.

As the electrode 29 moves out of engagement with the electrode 75 an arc is drawn between the electrodes. The downward 20 movement of the electrode 29 and the length of the arc struck is limited by the engagement of the pawl 35 with the pin 37. After an arc is struck the feeding mechanism of the lamp will remain inoperative until the 25 increased voltage of the arc, resulting from the consumption of the electrodes or from other causes, becomes great enough to again cause the coil 45 to be operatively energized, whereupon the contact 58 will again be 30 moved into position to close the switch in circuit with coil 13 formed by the contacts 62 and member 58, and the feeding operation will be repeated.

Should current fail to flow between the 35 electrodes on account of undue consumption of the latter or from other causes, the winding 13 is so arranged as to form a shunt about the coil 45 which will take enough of the current flowing between the lamp terminals to prevent injury to the coil 45, while at the same time the voltage drop between the 40 terminals of the coil 13 will be sufficient to maintain the operative energization of the coil 45.

45 It will readily be seen that with the mechanism shown an arc of constant length is struck after each feeding operation of the lamp. It will be understood that in the feeding operation the member 27 is pulled 50 through the yoke of the clutch 34 after the pawl engages the upper pin 40 an amount equal to the increase in the arc length due to the consumption of the electrodes occurring since the preceding operation.

55 When it is desired to lower the cross-head 26 in order to trim the lamp, or for other causes, the clutch 34 may be rendered inoperative by pushing rod 32 upward.

The air entering the globe 81 through the 60 aperture 82 when heated passes upward through the chimney 1 and out into the atmosphere through the aperture 9. The ascending air current steadies the arc and carries the arc products out of the lamp.

35 The lamp which I have herein described

and illustrated is intended more particularly for use in an alternating constant current circuit with electrodes giving what is known as a flaming or luminous arc, though the lamp is not necessarily limited to such use. 70 The electrodes employed may be of any suitable character. I have obtained excellent results by the use of a lower electrode formed of about ninety parts of titanium carbide and ten parts of carbon, and an upper electrode 75 comprising a shell of carbon and a filling composed principally of titanium carbide. I make no claims to such electrodes in my present application, however, as they are claimed in my application Serial No. 80 184,564, filed December 10, 1903.

The mechanism described and illustrated is simple, compact, and comparatively inexpensive to make. It is especially adapted for use in lamps in which the arc current is 85 quite small as compared with the arc currents ordinarily employed in arc lamps.

While I have hereinbefore described and illustrated the best form of my invention now known to me, it will be obvious to those 90 skilled in the art that changes may be made in the form of the invention disclosed without departing from its spirit, and I do not intend the claims hereinafter made to be limited to the particular construction disclosed more than is made necessary by the 95 state of the art.

What I claim as new and desire to secure by Letters Patent of the United States, is:—

1. In an arc lamp, a movable electrode, a 100 support therefor comprising a pair of parallel members, an arc length limiting means in coöperative relation with one of said members, and an arc striking means in coöperative relation with the other of said members.

2. In an arc lamp, an electrode, a clutch normally holding said electrode stationary, a second electrode, and means for moving said second electrode to actuate said clutch 110 to release the electrode held by it.

3. In an arc lamp, a tube, an electrode projecting therefrom, a clutch normally holding the electrode locked in the tube but arranged to release said electrode when 115 raised, a second electrode, and means for moving it toward the other electrode to raise the clutch and release said electrode.

4. In an arc lamp, an electrode receiving shell, an electrode in said shell, a clutch for 120 locking said electrode in said shell, a second electrode, and means for moving said second electrode into engagement with said clutch whereby the first mentioned electrode will be released.

5. In an arc lamp, an electrode, a clutch having an opening into which one end of said electrode extends, said electrode being normally locked in said clutch, a second electrode movable toward but not through the 130

opening in said clutch, and means for moving said second electrode toward the first mentioned electrode to engage said clutch and move it whereby the first mentioned 5 electrode will be released.

6. In an arc lamp, an upper electrode, a lower electrode, a support for the upper electrode comprising a movable member located adjacent the upper electrode and a 10 clutch associated therewith arranged to normally engage said upper electrode and to disengage the same when said movable member is raised, and means comprising a shunt electromagnet for raising said lower electrode into engagement with said movable member, whereby the upper electrode is released and permitted to gravitate into engagement with the lower electrode and the shunt magnet then deenergized, thereby permitting 15 the lower electrode to drop away from the upper to establish the arc.

7. In an arc lamp, a stationary framework, an upper electrode, a clutch therefor comprising a yoke surrounding said electrode and a pawl having its upper end pivotally connected to said framework and its lower end pivotally connected to said yoke, a lower electrode in alignment with the upper electrode, and means for moving 25 it into engagement with the first mentioned electrode or said yoke to move the latter, whereby the first mentioned electrode will be released from its clutch.

8. In an arc lamp, a pair of electrodes, 35 and means controlled by the arcing end of one of said electrodes for causing the other electrode to be fed until its arcing end reaches a predetermined position at each feeding operation of the lamp.

40 9. In an arc lamp, an electrode, a clutch normally holding said electrode stationary, a second electrode, and means actuated by said second electrode for tripping said clutch when the arcing end of the latter electrode reaches a predetermined point.

10. In an arc lamp, a pair of electrodes, means for moving one of said electrodes, and means controlled by the arcing end of the latter electrode for causing the other 50 electrode to be moved toward it.

11. In an arc lamp, an electrode, a second electrode, means for moving the said second electrode toward the other, and means controlled by the arcing end of the second electrode for causing the other electrode to be moved toward it when the arcing end of the 55 said second electrode reaches a predetermined point.

12. In an arc lamp, a pair of electrodes arranged to be movable toward each other, a holding device for one of said electrodes, and means actuated by the other electrode

when its arcing end reaches a predetermined position for releasing said holding device.

13. In an arc lamp, a gravity-actuated 65 electrode, a second electrode, a restraining clutch for said gravity-actuated electrode, and means for actuating said second electrode, said parts being so arranged that the said second electrode trips said clutch when its arcing end reaches a predetermined point.

14. In an arc lamp, an electrode, a holding device for said electrode, a second electrode, means for actuating said second electrode, and a tripping member extending 75 from said holding device into the path of movement of the arcing end of the said second electrode.

15. In an arc lamp, a pair of electrodes arranged for movement toward each other, 80 a restraining device for one of said electrodes, actuating means for the second electrode, and controlling means for said restraining device extending into the path of movement of the arcing end of the said 85 second electrode.

16. In an arc lamp, a pair of electrodes arranged for movements toward each other, actuating means for one of said electrodes, and a controlling device for the second electrode having a member arranged in the path 90 of movement of the arcing end of the other electrode.

17. In an arc lamp, a gravity-actuated electrode, a second coöperating electrode, a 95 holding clutch for said gravity-actuated electrode having a member extending into the path of movement of the arcing end of the second electrode, and means for actuating said second electrode.

18. In an arc lamp, a pair of electrodes arranged for movements toward each other, actuating means for one of said electrodes, and a controlling device for the second of 105 said electrodes movable upon a fixed support, said controlling device having a portion extending into the path of movement of the arcing end of the first electrode.

19. In an arc lamp, a gravity-actuated electrode, a second electrode, a holding 110 clutch for said gravity-actuated electrode mounted on a fixed support, actuating means for said second electrode, and a clutch actuating member normally occupying a predetermined fixed position in the path of movement of the arcing end of the second electrode.

In witness whereof I have hereunto set my hand this 26th day of April, 1905.

JOHANNES HÄRDÉN.
